UNITED STATES PATENT OFFICE.

GEORGE J. LEWIS, OF ST. PAUL, MINNESOTA.

PERFUMED PINCUSHION.

No. 920,968.

Specification of Letters Patent. Patented May 11, 1909.

Application filed January 18, 1907. Serial No. 352,847.

To all whom it may concern:

Be it known that I, GEORGE J. LEWIS, a citizen of the United States, residing at St. Paul, in the county of Ramsey and State of Minnesota, have invented a new and useful Improvement in Perfumed Pincushions, of which the following is a specification.

My invention relates to an improved perfumed pin cushion and has for its object a device of its kind containing sachet powder or other perfume material and which represents a miniature flour sack, thus producing a new and useful article of manufacture and an advertising novelty employing a minimum amount of sachet powder.

In the accompanying drawings, forming part of this specification, Figure 1 is a side view of my invention; Fig. 2 shows the cotton batting or other material which is used as a filling; and Figs. 3, 4, and 5 illustrate the different steps and the parts which are used during the manufacture of my invention.

In a general way, my invention consists of a miniature flour sack which is filled or stuffed with soft material such as cotton batting or wadding and perfumed with sachet powder and closed. Such a device can be used as a pin cushion or for other purposes and provides a convenient and desirable means for advertising brands of flour or other materials by printing or otherwise inscribing advertising matter, such as trade marks upon its surface.

In the drawings A is a bag representing a miniature flour sack which is filled with soft material. This material is represented in Fig. 2 and consists of a strip of cotton batting which is of suitable length to be inserted when doubled over a blade 3 in the bag A as illustrated in Figs. 3 and 4. Before the cotton batting is inserted a thin layer of the strip is thrown back and a quantity of sachet powder 1 is spread under the strip which is subsequently returned to its original position. The strip of cotton

batting is doubled over the blade with its powdered side out and the sack is drawn down over the cotton batting. While the parts are supported by the blade a suitable hand implement such as the rod 4 is thrust into the sack. After the bag is filled it is drawn off of the blade and the cotton batting is shaped into the sides and lower corners of the sack by means of the rod 4. The sack is then placed in a vise 5 and its mouth closed by stitching 6. The ears 7 are left protruding and are fastened by half-hitches of the stitching thread in the same manner as is customary in closing sacks of flour. The jaws 8 of the vise are closed by a foot lever 9 and a connecting cord 10 so as to pinch and hold the mouth of the sack closed while it is being sewed.

In accordance with the patent statutes, I have described the principle of operation of my invention, together with the apparatus which I now consider to represent the best embodiment thereof, but I desire to have it understood that the construction shown is only illustrative and that the invention can be carried out by other means and applied to uses other than those above set forth within the scope of the following claim.

Having described my invention, what I claim as new and desire to protect by Letters Patent, is:—

As a new article of manufacture, a sack, a strip of soft material folded with laps within said sack, perfumed powder embedded in the laps of said strip adjacent to a side of said sack and means for holding said sack closed.

In testimony whereof, I have signed my name to this specification, in the presence of two subscribing witnesses.

GEORGE J. LEWIS.
